UNITED STATES PATENT OFFICE.

FRANCIS J. SCARR, OF HASBROUCK HEIGHTS, NEW JERSEY.

COMBINED SIGHT AND CLINOMETER.

1,316,391.

Specification of Letters Patent. Patented Sept. 16, 1919.

Application filed May 15, 1918. Serial No. 234,840.

To all whom it may concern:

Be it known that I, FRANCIS J. SCARR, residing at Hasbrouck Heights, Bergen county, in the State of New Jersey, have invented 5 certain new and useful Improvements in Combined Sights and Clinometers, of which the following is a full, clear, and exact specification.

My invention relates to improvements in 10 combined sights and clinometers, and the same has for its object more particularly to provide a simple, efficient and accurate device which will serve both as a sight and a clinometer.

15 Further, said invention has for its object to provide a device of the character specified which is particularly adapted for use in connection with any type of gun supported upon a fixed mounting, which mounting may be 20 either permanent or movable.

Further, said invention has for its object to provide a device of the character specified which is particularly adapted for use in laying a gun for indirect firing.

25 Further, said invention has for its object to provide a device of the character specified by means of which the elevation and range may be accurately determined, and thereupon to permit of the piece being duly aimed 30 to reach the desired target or objective.

Other objects will in part be obvious and in part be pointed out hereinafter.

To the attainment of the aforesaid objects and ends my invention consists in the novel 35 details of construction, and in the combination, connection and arrangement of parts hereinafter more fully described and then pointed out in the claims.

In the accompanying drawings forming 40 part of this specification wherein like numerals of reference indicate like parts—

Figure 1 is a side elevation of a machine gun equipped with one form of combined sight and clinometer construction according 45 to and embodying my said invention;

Fig. 2 is an enlarged detail face view of the sight and clinometer detached from the piece, with the leaf adjusted to an upright position, and

50 Fig. 3 is a side elevation of the same. Referring to said drawings 10 denotes the combined sight and clinometer as a whole, comprising a base 11, adapted for securement to a gun, and a curved sight leaf 12 55 which is pivotally secured at its lower end

to said base 11. The sight leaf 12 is slotted longitudinally, thereby forming two parallel side members 13, 14 which are preferably curved to correspond to the arc of a circle having a radius equal to the distance between 60 the front and rear sights of the gun upon which the device, as a whole, is mounted. The inner surfaces of the side members 13 and 14 are provided with longitudinal grooves 15 within which works the sliding 65 sight, hereinafter described.

The lower end of the sight leaf 12 is notched to form the battle sight 16. The sight leaf 12 is provided at its lower end with registering transverse openings 17 to 70 receive a pin by means of which the sight leaf 12 is pivotally attached to the base 11 upon the gun. The sight leaf 12 is further provided at its lower end with forwardly projecting shoulders 18 which 75 are adapted to engage the sight base spring when the device is raised for use, and to be held firmly under tension of said spring in its upright position.

The front surface of the side member 13 80 of the sight leaf 12 is provided with a mil scale, and the corresponding surface of the side member 14 is provided with a range scale which may be calibrated in yards or meters, as desired.

85 19 indicates a slide, curved to correspond to the curvature of the side members 13, 14, of the sight leaf 12, and having laterally projecting tongues 20 which are received within the longitudinal grooves 15 formed 90 in the side members 13, 14. The slide 19 is cut away at its lower end, as indicated at 21, in order to permit the lower end of the slide 19 to clear the pin passing through the holes 17 in the side members 13, 14, when 95 the slide 19 is moved to its lowermost position. The slide 19 is provided, adjacent its lower end, with an oval opening having a notch in its base constituting a direct fire sight notch 22, and its front surface is provided with a range scale, which reads in the same units of length as the range scale on the side member 14 of the sight leaf 12. The graduation marks of the range scale on the slide 19 are adapted to register with the 100 graduation marks of the mil scale on the side member 13.

105 In its front surface, the slide 19 is provided with a recess 23 to receive the base 24 of a spirit level 25, which is held in place 110

by screws 26 passing through holes in the base 24 and engaging threaded holes 27 in the slide 19.

Secured to the slide 19, as by screws 28, 5 is a clamp 29 having a laterally extending projection 30 registering with the outer surface of the side member 13. The projection 30 of the clamp 29 carries a set screw 31, by means of which said slide 19 may be 10 firmly held in position after the same has been properly adjusted upon the sight leaf 12. It will be understood that upon loosening the set screw 31, the slide 19 may be adjusted upon the sight leaf 12 until it is in 15 its proper position, after which, the set screw 31 is tightened to hold the same firmly in its adjusted position.

In operation, if it is desired to use the gun for direct fire, it is merely necessary so 20 to adjust the slide 19 upon the sight leaf 12 that the direct fire sight 22 registers with the appropriate mark of the range scale on the side member 14 corresponding to the proper range. The gun is then operated in 25 the usual manner.

If the range and the angle of sight is given, the slide 19 is so adjusted upon the sight leaf 12 that the mark of the range scale on the slide 19, which corresponds to 30 the given range, registers with the mark of the mil scale on the side member 13, corresponding to the given angle of sight. After the slide has been thus adjusted upon the sight leaf 12 and clamped in position by 35 the set screw 31, the gun is adjusted upon its support until the spirit level 25 assumes the true level position, at which time the gun will have the proper elevation or depression for firing under the given conditions. 40

On firing over a mask, if it is desired to determine the minimum range, the slide 19 is set in the usual manner, to indicate the range and angle of sight of the mask. 45 The slide 19 is then moved upwardly a distance equal to the number of mils required by the table of mask clearances. The gun is then aimed at the crest of the mask, and clamped against movement. The slide 50 19 is now moved upwardly with respect to the sight leaf 12 until the level 25 is in its level position. The range now indicated upon the slide 19 is the minimum range with full mask clearance which it was de- 55 sired to ascertain.

If it is desired to use the battle sight 16, the slide 19 is removed by sliding it from the sight leaf 12, at the upper end thereof, after which the sight leaf 12 is lowered, thus 60 causing the battle sight 16 to assume its proper position for use.

Having thus described my said invention, what I claim and desire to secure by Letters Patent is:—

65 1. A device of the character described

comprising a support calibrated to indicate vertical angles, a member movably mounted with respect thereto having a sight opening, and calibrated to indicate horizontal distances, and means operatively associated 70 with said movable member for indicating when the piece is duly trained upon the target or objective, substantially as specified.

2. A device of the character described comprising a support calibrated to indicate 75 vertical angles, a member movably mounted with respect thereto having a sight opening, and calibrated to indicate horizontal distances, and means carried by said movable member for indicating when the piece is 80 duly trained upon the target or objective, substantially as specified.

3. A device of the character described comprising a support calibrated to indicate 85 vertical angles, a member movably mounted with respect thereto having a sight opening, and calibrated to indicate horizontal distances, and a level indicating device operatively associated with said movable member for indicating when the piece is duly trained 90 upon the target or objective, substantially as specified.

4. A device of the character described comprising a support calibrated to indicate vertical angles, a member movably mounted 95 with respect thereto having a sight opening, and calibrated to indicate horizontal distances, and a spirit level operatively associated with said movable member for indicating when the piece is duly trained upon 100 the target or objective, substantially as specified.

5. A device of the character described comprising a support calibrated to indicate vertical angles, a member movably mounted 105 with respect thereto having a sight opening, and calibrated to indicate horizontal distances, and a spirit level carried by said movable member for indicating when the piece is duly trained upon the target or objective, substantially as specified. 110

6. A device of the character described comprising a support provided with a scale to indicate vertical angles and with a scale to indicate horizontal distances, a member 115 movably mounted upon said support having a sight opening, and indicating means associated therewith and coacting with the scale of horizontal distances in said support, said movable member being provided with a scale to indicate horizontal distances co-acting 120 with the scale of vertical angles in said support, and means for indicating when the piece is duly trained upon the target or objective, substantially as specified. 125

7. A device of the character described comprising a curved support calibrated to indicate vertical angles, a member movably mounted upon said support having a sight opening and calibrated to indicate hori- 130

zontal distances, and means operatively associated with said movable member for indicating when the piece is duly trained upon the target or objective, substantially as specified.

8. A device of the character described comprising a support having a curvature corresponding to the arc of a circle, said support being calibrated to indicate vertical angles, a member movably mounted upon said support having a sight opening and calibrated to indicate horizontal distances, and means operatively associated with said movable member for indicating when the piece is duly trained upon the target or objective, substantially as specified.

9. A device of the character described comprising a support having a curvature corresponding to the arc of a circle whose radius is equal to the distance between the front and rear sights, said support being calibrated to indicate vertical angles, a member movably mounted upon said support having a sight opening and calibrated to indicate horizontal distances, and means operatively associated with said movable

member for indicating when the piece is duly trained upon the target or objective, substantially as specified.

10. A device of the character described comprising a support having a curvature corresponding to the arc of a circle whose radius is equal to the distance between the front and rear sights, said support being calibrated to indicate vertical angles, a member movably mounted upon said support having a sight opening and calibrated to indicate horizontal distances, and a spirit level carried by said movable member for indicating when the piece is duly trained upon the target or objective, said spirit level being positioned radially with respect to said support, substantially as specified.

Signed at the city of New York, in the county and State of New York, this 13th day of May, one thousand nine hundred and eighteen.

FRANCIS J. SCARR.
